UNITED STATES PATENT OFFICE

WILLIAM P. ARNOLD, JR., OF HOUSTON, TEXAS, ASSIGNOR TO SINCLAIR REFINING COMPANY, OF NEW YORK, N. Y., A CORPORATION OF MAINE

TANK SAMPLER

Application filed October 23, 1929. Serial No. 401,933.

This invention provides an improved apparatus for taking samples of liquids from tanks maintained under superatmospheric pressure. This apparatus is of special value 5 and application in connection with the handling and storing of petroleum oils but, as will be apparent, it is of more general application.

The necessity for minimizing loss of the 10 more volatile portions of petroleum oils from storage tanks through "breathing" of the tanks has caused the general adoption of closed tanks connected to a "pressure bag" or "balloon" for the maintenance of an approximately constant pressure somewhat above atmospheric pressure in the tanks for this purpose. Previous to the adoption of this type 15 of tankage, samples were commonly taken by lowering a "thief" through an opening in the tank left open to the atmosphere during the taking of the sample. This common practice, of course, is not available for taking samples from tanks maintained under superatmospheric pressure. This invention provides 20 an improved apparatus for this purpose.

In brief, the apparatus of this invention 25 comprises a closable chamber adapted to be affixed to the tank and having an opening adapted to register with a corresponding opening in the tank, a carrier for the sampling container for carrying this container from within the chamber through these openings into the tank and back into this chamber by operating means arranged outside of the 30 chamber, a door adapted to close these openings when the carrier is within the chamber with operating means arranged outside of the chamber, and another door providing access to the chamber from outside for closing 35 the chamber when the first mentioned door is open.

The invention will be further described in 40 connection with the accompanying drawings which illustrate an apparatus embodying the invention. In the accompanying drawings Fig. 1 is a fragmentary elevation, Fig. 2 is a fragmentary end view and Fig. 3 is a plan view of the apparatus.

Referring to the drawings, the chamber 1 45 is adapted to be affixed to a tank so that the

nipple 2 defining an opening 3 into the chamber extends into a corresponding opening in the tank forming a vapor tight connection between the chamber and the interior of the tank. A carrier 4 adapted to receive and hold a sample bottle 5 is supported by a cable 6 running through a stuffing box 7 to a winch 8 outside of the chamber. The carrier 4 is proportioned and the cable 6 is positioned so that the carrier may be lowered from within 55 the chamber 1 through the opening 3 to any required depth in the tank to which the chamber 1 is affixed. A sliding door 9 is provided for closing the opening 3 when the carrier 4 is within the chamber 1. An operating extension 10 running through a stuffing box 11 is provided for moving the door 9 across the opening 3, and cam-clamps 12 and 13 are provided for tightly closing this door when it is 60 in position over the opening 3. Another door 14 provided with means 15 for maintaining it tightly closed when the door 9 is open is arranged to afford access to the chamber 1.

The operation of taking the sample from 65 the tank with the apparatus of this invention is as follows: A sample bottle is placed in the carrier 4 through the door 14 and this door is then tightly closed. The door 9 is 70 then opened and the carrier 4 with the sample bottle is lowered through the opening 3 into the tank to the required depth for taking the desired sample by means of the winch 8. The sample bottle containing the desired sample is then pulled back through the opening 3 and the door 9 is again tightly closed. The sample bottle containing the desired sample is then removed from the carrier 4 75 through the door 14. Thus, a sample is secured with a minimum of vapor loss and 80 without any substantial expulsion of vapor from within the tank even though the tank be under superatmospheric pressure.

I claim:

An apparatus for taking samples of 85 liquids from tanks maintained under superatmospheric pressure comprising a closable chamber adapted to be affixed to the tank and having an opening adapted to register with a corresponding opening in the tank, a carrier adapted to receive and hold a sampling 90

100

container and means, operable from without said chamber, for carrying said carrier from within said chamber through said openings into the tank and back, a door, operable from without said chamber, adapted to close said openings when said carrier is within said chamber and means operable from without said chamber adapted to exert mechanical pressure on said door to seal said openings when the carrier is within the chamber, and a door providing access to said chamber from without adapted to close said chamber when the first mentioned door is open.

15 In testimony whereof I affix my signature.
WILLIAM P. ARNOLD, JR.
